Patented Apr. 2, 1912.

UNITED STATES PATENT OFFICE.

EUGENE S. MICHENER, OF NEW CASTLE, PENNSYLVANIA.

MEANS FOR REMOVING CARBON FROM ENGINE-CYLINDERS.

1,022,040.

Specification of Letters Patent.

Patented Apr. 2, 1912.

Application filed May 31, 1910. Serial No. 564,255.

To all whom it may concern:

Be it known that I, EUGENE S. MICHENER, a citizen of the United States, residing at New Castle, in the county of Lawrence, State 5 of Pennsylvania, have invented certain new and useful Improvements in Means for Removing Carbon from Engine-Cylinders; and I do hereby declare the following to be a full, clear, and exact description of the invention, such as will enable others skilled in the art to which it appertains to make and use the same.

The invention relates to means for removing carbon from engine cylinders.

15 The primary object of the invention is to provide means whereby accumulated carbon within a gas or other engine cylinder may be readily and easily removed, thereby promoting the proper working of the engine 20 and thus avoiding injury to its cylinders.

Another object of the invention is to provide means for removing carbon from an engine cylinder without requiring dismantling of the engine, thereby enabling an 25 unskilled person to thoroughly cleanse the cylinder so as to free the same of carbonaceous substance in a quick and convenient manner and at the same time obviating any possibility of soiling the clothing or hands 30 of such person.

A further object of the invention is to provide a means for removing carbon from engine cylinders of varying types such as gas or other engines without requiring the 35 removal of the piston therefrom and also without the necessity of any labor on the part of a person as one cylinder of the engine may be cleaned while the other cylinder is being operated.

40 With these and other objects in view the herein described means employed in carrying out the same is accomplished by the steps and in the manner as will be herein-after more fully described in detail, and 45 illustrated in the accompanying drawings, while the novelty of the invention will be pointed out in the claims hereunto appended.

In the drawings:—Figure 1 is a fragmentary sectional view of a gas engine and 50 its piston with the means for cleaning the carbon from the cylinder shown in position therein. Fig. 2 is a detail plan view of the means employed for cleaning the carbon from the engine cylinder, the said means 55 being shown on an enlarged scale. Fig. 3

is a side elevation of a tool for removing the said means from the engine cylinder.

Similar reference characters indicate corresponding parts throughout the several views in the drawings.

60 Referring to the drawings by numerals 5 designates generally the cylinder of a gas engine which is of the ordinary type shown in vertical position the same being provided with a threaded opening in its head to detachably receive the usual spark plug 6 for igniting the compressed gases on the compression stroke of the piston 7 working within said cylinder. This type of cylinder 65 is merely shown for the sake of illustrating the manner of use of the means for removing the carbon accumulated therein as will be hereinafter more fully described and also the method and manner in carrying the said 70 means into operation.

75 The means above mentioned comprises a chain of loosely joined coiled rings 8 each ring being formed of a single strand of wire 80 bent to provide a series of convolutions 9 the same being arranged in juxtaposition and of corresponding diameter to each other. The single strand of wire is of the same cross sectional area throughout its entire length and by the arrangement of the convolutions in juxtaposition to each other one 85 strand from the wire will lie close to and upon the adjacent coil and said rings are connected by passing the coils of one ring and then by twisting the latter ring it will 90 link with the said other ring after the latter has passed the remaining free end of the second named ring. The chain of loosely connected rings 8 may be varied either by 95 increasing or decreasing the same as the occasion may require.

100 Connected to the outer rings 8 of the chain are arcuate shaped terminal members 10 each being formed of a single strand of wire helically wound, the same being separated from each other a desirable distance apart whereby the said members assume an arcuate shape. The convolutions of each terminal member extend radially from the 105 related terminal ring of the chain, and by virtue of this construction, sufficient space exists between the convolutions to prevent accumulations of scale and the like lodging therebetween and choking and impeding 110

the scraping action of the member. Furthermore, by virtue of these terminal members, the chain will be prevented from moving underneath the valves, since each valve 5 lifts approximately a quarter of an inch and the diameter of each terminal member is considerably greater than a quarter of an inch, so that should a terminal member move to a position in registration with the valve, 10 the latter will shove the member back from the port, and thus the proper working of the valve is not interfered with during removal of the carbon from the cylinder. It will be noted also that the terminal members are 15 loosely mounted on the terminal rings of the chain and are free to move in either direction on said rings, the value of this being that the terminal members may act as hammers when in motion to knock scale and the 20 like from the cylinder wall.

The mode or method of carrying the above means into operation consists in removing the spark plug 6 from one cylinder 5 of an engine of the twin cylinder type or multi- 25 plied cylinders whereupon the chain is introduced through the spark plug opening in said cylinder 5 into its explosive chamber and thereafter about $\frac{1}{4}$ pint of kerosene oil is poured into the cylinder through the 30 spark plug opening and then the said spark plug is replaced in the opening in the cylinder head. Now the ignition circuit of the cylinder is cut off whereupon the engine is started by running the same with the re- 35 maining cylinder or cylinders for a few minutes, so that the piston 7 will reciprocate within the cylinder moving with it the chain

which will remove all carbon accumulated within the explosion chamber of the cylinder. After the explosion chamber has been 40 cleaned in this manner the spark plug 6 is again removed from its opening in the cylinder head and by the employment of a hook member 11 which is of the required length is inserted through the spark plug opening 45 in the head of the cylinder 5 and engaged with the chain so that it may be readily and quickly removed from the said cylinder. The remaining cylinder or cylinders of the engine are cleaned and the removal of car- 50 bon from the explosion chamber or chambers thereof is accompanied by repeating the foregoing procedure in the mode and manner set forth.

What is claimed is:—

1. A cleaner comprising a chain, and arcuate helical wire elements loosely mounted on the terminal links of the chain and adapted to slide in either direction on said links.

2. A cleaner comprising a chain having a plurality of rings, loosely connected to each other, each ring being formed of a single strand of wire bent to provide a series of convolutions, and arcuate helical wire elements loosely mounted on the terminal rings of the chain and adapted to slide in either direction on said terminal links.

In testimony whereof, I affix my signature, in presence of two witnesses.

EUGENE S. MICHENEN.
